UNITED STATES PATENT OFFICE

151,753

DESIGN FOR A COMB

John Frickel, Greenwich, Conn., assignor to Vulcanized Rubber and Plastics Company (Incorporated), New York, N. Y., a corporation of New York

Application March 25, 1947, Serial No. 137,870

Term of patent 7 years

(Cl. D86—8)

To all whom it may concern:

Be it known that I, John Frickel, a citizen of the United States of America and a resident of Greenwich, Fairfield County, and State of Connecticut, have invented a new, original, and ornamental Design for a Comb, of which the following is a specification, reference being had to the accompanying drawing, forming part thereof, in which—

Fig. 1 is a side elevation of a comb, embodying my design.

Fig. 2 is an end view thereof.

The essential features of my design reside in the portions shown in full lines.

I claim:

The ornamental design for a comb, as shown and described.

JOHN FRICKEL.
